UNITED STATES PATENT OFFICE.

CHRISTIAN H. BAUMEISTER, OF DES MOINES, IOWA.

DISPLAY-RACK FOR WHIPS.

1,140,102.

Specification of Letters Patent.

Patented May 18, 1915.

Application filed January 15, 1914. Serial No. 812,345.

To all whom it may concern:

Be it known that I, CHRISTIAN H. BAUMEISTER, a citizen of the United States, residing at Des Moines, in the county of Polk and State of Iowa, have invented certain new and useful Improvements in Display-Racks for Whips; and I do hereby declare the following to be a full, clear, and exact description of the invention, such as will enable others skilled in the art to which it appertains to make and use the same.

This invention relates to display racks for whips and more particularly to display racks to be placed in front of the stores or 15 in the windows and designed to retain various samples of whips.

A further object of this invention resides in the construction of a display rack capable of holding a greater number of samples of 20 whips for display.

A still further object of this invention resides in the provision of means for fixedly securing the whips upon the rack for preventing removal of the same by unauthorized persons. And a still further object of 25 this invention resides in the construction of a rack, simple in construction, ornamental in design, efficient in purpose and which can be manufactured at a nominal cost.

These and other objects will more fully appear and the nature of the invention more clearly understood by the construction, combination and arrangements of the parts thereof as described in the following specification, defined in the appended claims and 35 illustrated in the accompanying drawings, in which,

Figure 1 is a side elevation of my device, showing the same as it appears with the 40 whips secured thereon for displaying the same. Fig. 2 is a vertical, longitudinal, sectional view of my invention showing the interior thereof and the means for mounting the inner cylinder upon the base formed by the bottom of the outer casing, the same 45 being held together at their respective bases. Fig. 3 is a transverse, sectional, view on the line 3—3 of Fig. 2 showing the detail construction of the means for securing the 50 whips upon the rack.

Like reference characters denote corresponding parts throughout the several views of the drawings and reference being had to the same, 1 denotes the outer casing preferably cylindrical in form and has arranged 55 at the top thereof the inwardly and up-

wardly inclined annular flange 2. The bottom of the casing is indented inwardly and extends upwardly for a short distance within the same and partakes of the frusto-conical form having an inclined diverging wall 3 and the frustum or supplemental base 4 and upon the base 4 is mounted the inner conical shaped cylinder 5 formed with the apex 6. The base 7 of the cylinder 5 is of a diameter equal to that of the frustum or supplemental base 4 of the bottom of the casing 1, the base 60 of the cylinder 5 and the supplemental base 4 of the bottom of the cylinder are each provided with the registering apertures 8 65 through which is adapted to pass the bolt 9, the head thereof being designed to rest against the inner side of the base 7 of the cylinder 5 and having arranged at its opposite end within the bottom of the casing 1 70 the thumb nut 10 designed to engage the threads of the bolt 9 for holding the base 7 and the base 4 in rigid engagement with each other.

Surrounding the outer wall of the casing 80 1 and fixedly secured thereto are the upper and lower retaining means 11, for holding the whips thereon and may be made of leather or other flexible material, the retaining members comprising an inner strap 85 12 circular in direction and of a diameter to snugly fit the outer periphery of the casing 1, and upon this strap is sewed or otherwise fixedly secured thereto a second strap 13, and between which at spaced intervals 90 and arranged in series are secured the pairs of metal loops 14 for retaining the whips 17 in position therebetween, and to secure the whips 17 between the loops 14 is provided the lacing strap 15, which strap is laced 95 through the loops 14 and over the whips 17 as shown in Fig. 3, and by drawing the strap 15 to sufficient tension around the holder, the whips 17 are thereby held in secured position between each respective pairs 100 of loops and under the strap 15, the strap 15 is provided with the buckle 16 for holding the free ends thereof together when the strap 15 has been drawn sufficiently tight for binding the whips 17 in secured position between the loops 14 and the straps 15. Surrounding the inner cylinder 5 of the 105 rack and arranged thereon in a position somewhat elevated above the plane of the straps 11 upon the outer wall of the casing 1 are similar retaining means as those upon the casing 1, the only difference being

110

that the straps are formed of a shorter length than the first mentioned straps to provide for the reduced diameters of the cylinder 5 for fitting the same upon the periphery of the inner cylinder.

My display rack may be made of any kind of metal or bent wood sufficient to form the same to perform the functions for which the same is designed.

- 10 The assembling of the parts constituting my invention is sufficiently obvious from the drawings and the foregoing description thereof to warrant further detail description, but I desire to here state that my device is not for the purpose of displaying whips loosely thereon for the ready removal of the same for the sale thereof, but is designed primarily for sample whips either for indoor or outdoor display and to safely 15 secure the sample whips contained thereon against removal by unauthorized persons. The strap or bands for retaining the whips are secured to the respective cylinders by any well known means and while I have 20 here described the same as being formed of leather it is to be understood that I do not restrict myself to making the same of this product but may use any other which may be efficiently used.
- 25 While I have here shown and described the preferred form of my invention, I hereby reserve the right to make such alterations and variations therein from time to time which I may deem expedient and which 30 will not depart from the spirit of this invention or conflict with the scope of the appended claims.

Having thus fully described my invention

what I claim as new and desire to secure by Letters Patent is:—

1. In combination with an outer cylinder and an inner conical cylinder rigidly secured therein, of a plurality of retaining means attached to said cylinders for holding articles securely, placed for display upon the said cylinders, each of said retaining means comprising a flexible inner member; a plurality of metal loops arranged in pairs and secured to the said flexible member by a second flexible member passed 45 through said metal loops and fixedly secured to the first mentioned flexible member between each pair of metal loops; a lacing strap surrounding the said cylinders and being disposed within the said metal loops, 50 and suitable means for securing the ends of said lacing strap together.

2. In a display rack of the class described comprising an outer cylinder and an inner conical cylinder, a plurality of retaining means attached thereto, each of said retaining means comprising a plurality of metal loops, secured in pairs to a flexible supporting member, said supporting member being adjusted to the diameter of the 55 cylinders whereon they rest; a lacing strap disposed through the said metal loops, and suitable means to secure the ends of the said lacing strap.

In testimony whereof I have signed my 70 name to this specification in the presence of two subscribing witnesses.

CHRISTIAN H. BAUMEISTER.
